UNITED STATES PATENT OFFICE.

RAYMOND C. LONGVALL, OF WORCESTER, MASSACHUSETTS, ASSIGNOR TO WARP COM-
PRESSING MACHINE COMPANY, OF WORCESTER, MASSACHUSETTS, A CORPORATION
OF MASSACHUSETTS.

ARRANGEMENT OF SPINDLES FOR CREELS.

Application filed April 11, 1927. Serial No. 182,867.

My invention relates to creels or spool stands, such as are employed for supporting a plurality of spools, or yarn packages, so that yarn or thread may be evenly led from the packages for winding on a warp beam, or for any other purpose.

My invention relates particularly to that type of creel in which the yarns, or threads, are drawn from the ends of the packages in the general direction of the longitudinal axes of the packages, this type of creel being known in the art as an end delivery creel, as distinguished from that type of creel in which yarn or thread is drawn off tangentially to the periphery of the cylindrical packages. In end delivery creels as heretofore constructed, it has been customary to arrange the spindles in pairs with their longitudinal axes converging toward a common point equidistant from the ends of the spindles, from which point the yarn is adapted to be drawn from a package on either spindle of a pair. With this arrangement of spindles in pairs it is possible to connect the inner end of one yarn package to the outer end of the other yarn package so that yarn may be removed from both spindles without interruption; in other words continuous drawing of yarn is possible with this arrangement.

By my invention, I provide an improved arrangement of spindles whereby yarn may be drawn continuously from a pair of spindles as heretofore without, however, making it necessary to arrange each pair of spindles in convergent relation. With my improved arrangement it is possible to arrange a pair of spindles with their axes in parallel relation and at the same time to draw yarn equally well from each of the spindles from a drawing point equidistant from the ends of the spindles. With all the spindles parallel, it is possible to provide more spindles within a given space than has been heretofore possible, with each pair of spindles having their axes in convergent relation. Inasmuch as the usual creel employs a very large number of spindles, it is possible by the employment of my invention, to either materially reduce the overall dimensions of a creel employing a given number of spindles, or given a certain space in which to place a creel, it is possible, by my invention, to provide a much greater number of par-

allel spindles within this space than has been heretofore possible when using spindles inclined toward each other. The above and other advantageous features of my invention will hereinafter more fully appear, reference being had to the accompanying drawings, in which—

Fig. 1 is a plan view, partly diagrammatic, of an improved spindle arrangement embodying my invention.

Fig. 2 is a vertical sectional view along the line 2—2 of Fig. 1.

Fig. 3 is an enlarged view taken from in front of one of the drawing points, showing the arrangement of the throw-over device for the arm.

Like reference characters refer to like parts in the different figures.

Referring first to Figs. 1 and 2, a portion of a creel stand is illustrated therein which generally consists of a base member 1 having spaced uprights 2, 2 extending vertically therefrom. The uprights 2 serve to carry a series of vertically spaced horizontal spindle rails 3, 3, each carrying a plurality of horizontally spaced spindles 4, 4, extending in parallel relation from the rails 3.

The creel also comprises a plurality of vertically spaced horizontal bars 5, 5, each of which carries a row of equally spaced thread eyes 6, 6, the distance between adjacent thread eyes 6 being twice the distance between a pair of spindles 4. As best shown in Fig. 1, each thread eye 6 is disposed half way between a pair of spindles 4, 4, so that the ends of a pair of spindles 4 are equidistant from the opening in the corresponding thread eye 6. As shown in Fig. 2, each row of thread eyes 6 is located in the same horizontal plane as a row of spindles 4 carried by a spindle rail 3.

The creel also provides a number of vertically extending supports 7, 7 which are located between the spindle rails 3 and the thread eye bars 5, the central axes of the support 7 being in line with the openings in the thread eyes 6, as clearly shown in Fig. 1. Each support 7 carries a series of light weight arms 8 pivotally mounted on pins 9, each pin 9 being located below the horizontal plane A—A Fig. 2, containing a thread eye 6 and a pair of spindles 4. Each arm 8 carries at its end a thread guide 10 which is located at such a distance from the axis

of the pivot pin 9 that the opening 11 in the thread guide may be swung into exact alinement with either one of the pair of spindles 4 located on opposite sides of the support 7, 5 as indicated by the full line and dotted line position of the arm 8 in Fig. 3. Stops 8^a and 8^b may be provided to limit the positions of each arm 8.

Having described the various elements entering into my improved arrangement, there will now be described the operation of the same, with reference to Fig. 1. Referring to the left hand portion of Fig. 1, there is shown a pair of spindles 4 with substantially full yarn packages 12^a and 12^b thereon, the thread or yarn 13 being led from the end of the left hand package 12^a through the thread guide 10 to the eye 6 which is adapted to draw from the pair of spindles in question. 10 The inner end of the left hand package 12^a is shown at 13^a as extending from the butt of this package 12^a to the front of the right hand package 12^b, so that when the left hand package 12^a is exhausted the thread 13 will be drawn continuously from the right hand package 12^b without interruption. It is obvious that a draft on the thread 13 will cause the yarn to be unwound endwise from the package 12^a, as indicated by the dotted lines, 15 and that the unwinding will proceed properly as long as the thread guide 10 remains in the position shown.

Referring now to the middle pair of spindles 4 shown in Fig. 1, the thread 13 is shown as having been nearly unwound from the left hand spindle, while the right hand spindle 4 carries a full package 12^b. As the last bit of thread unwinds from the left hand spindle 4 the thread portion 13^a extending from the butt of the exhausted spindle to the front of the full package 12^b will be drawn outwardly to the thread guide 10, as shown in dotted lines, and as the end of this thread portion is substantially fixed to the right hand package 12^b there will be immediately exerted a force on the thread guide 10 tending to swing the arm 8 in a clockwise direction about its pivot pin 9. As previously pointed out, the arm 8 is light in weight, and as the pull on the thread 13 acts through a relatively long lever arm, the pull is sufficient to swing the arm 8 from the full line position of Fig. 3 to the dotted line position. In this new position the opening 11 of the thread guide 10 is in alinement with the axis of the spindle with the full package 12^b as indicated in dotted lines with regard to the intermediate pair of spindles in Fig. 1.

Referring now to the right hand pair of spindles in Fig. 1, the left hand spindle 4 is shown as having been exhausted and the arm 8 is shown as having been thrown over, as previously described to bring its thread guide 10 into axial alinement with the full right hand spindle 4. In this position the

thread 13 is drawn through the thread eye 6 in precisely the same manner as it was drawn from the left hand spindle before the latter was exhausted. When this has occurred there obviously remains plenty of time for 70 the operator to doff the exhausted spindle and place a new package thereon.

When the exhausted spindle has been replenished the operator fastens the inner end of the package 12^b on the active spindle to 75 the outer end of the new package, so that when the right hand package 12^b is exhausted, the thread 13 will be drawn from the replenished spindle and the arm 8 will throw over from the right hand position to 80 the left hand position, as previously described.

From the foregoing, it is apparent that by my invention I have provided an improved arrangement of spindles for a creel or spool stand in which the spindles may be arranged with their axes parallel and thread drawn continuously from any pair of spindles endwise, without interrupting the continuity of the drawing operation. With my improved arrangement it is possible to place the spindles quite close together, thereby permitting more spindles to be mounted within a given space than has been heretofore possible when arranging the spindles in pairs with their axes converging toward the drawing point for a given pair of spindles.

In order to make more clear the particular advantage of my improved arrangement over the arrangement of converging spindles, 100 reference is made to my copending application, Serial No. 182,923, filed jointly with Arthur L. Remington, on April 11, 1927. The above mentioned copending application shows an arrangement of spindles in pairs 105 with their axes converging toward the drawing point, and the saving in space obtained by the use of the present invention is apparent from a comparison of the drawings of the present application and the drawings 110 in my copending application. The above mentioned copending application also shows an improved mounting for spindles, whereby an exhausted spindle may be withdrawn 115 from the row of active spindles and reversed for the purpose of doffing, and it is obvious that this particular mounting of spindles may be employed in connection with the present invention without departing from the nature and the scope thereof.

I claim,

1. An improved arrangement of spindles for creels, comprising a pair of horizontally extending spindles supported in parallel relation, with yarn packages thereon, a stationary thread eye located between said spindles and in the same horizontal plane therewith, and a pivotally mounted thread guide located between the ends of said spindles and said thread eye, said thread guide being adapt- 130

ed to move under the influence of gravity into alinement with either of said spindles.

2. In a device of the class described, a supporting member carrying a pair of parallel horizontal spindles each having a yarn package thereon, a stationary thread eye located between said spindles, through which yarn is adapted to be drawn endwise from said spindles, and a thread guide pivotally mounted on a horizontal axis between the ends of said spindles and said thread eye, said 10 thread guide in one position being adapted under the influence of gravity to aline itself with one of said spindles, and in its other position to aline itself with the other of said spindles.

3. In a device of the class described, a sup-

porting member carrying a pair of parallel horizontal spindles each having a yarn package thereon, a stationary thread eye located 20 between said spindles, through which yarn is adapted to be drawn endwise from said spindles, and a thread guide pivotally mounted on a horizontal axis between the ends of said spindles and said thread eye, said 25 thread guide in one position being adapted to aline itself with one of said spindles until the yarn thereon is exhausted, whereupon the traction of the yarn on the thread guide serves to lift said guide to a point where the 30 force of gravity drops it into alinement with the other of said spindles.

Dated April 5, 1927.

RAYMOND C. LONGVALL.
